ENDLESS MAGNETIC-TAPE CARTRIDGE

William David Cohen, Huntington, N.Y., assignor to
Systems Resources Corporation, Plainview, N.Y.

Filed Sept. 30, 1969, Ser. No. 19,352

Term of patent 14 years

Int. Cl. D14—01

U.S. Cl. D26—14

FIG. 1

FIG. 2

FIG. 3

FIG. 1 is a top plan view of an endless magnetic-tape cartridge embodying my design;

FIG. 2 is a front elevational view of the cartridge of FIG. 1;

FIG. 3 is a left end view of the cartridge as viewed in FIGS. 1 and 2;

FIG. 4 is a bottom plan view of the cartridge illustrated in FIGS. 1 and 2;

FIG. 5 is a rear elevation of the cartridge illustrated in FIGS. 1 and 2; and

FIG. 6 is a right end view of the cartridge as shown in FIGS. 1 and 2.

I claim:

The ornamental design for an endless magnetic-tape cartridge, substantially as shown.
